(57) **CLAIM**

The ornamental design for a stripping tool, as shown and described.

DESCRIPTION

FIG. 1 is a front view of a stripping tool, showing the new design;

FIG. 2 is a bottom view thereof;

FIG. 3 is a rear view thereof;

FIG. 4 is a rear, right-side and top perspective view thereof;

FIG. 5 is a rear, left-side and top perspective view thereof;

FIG. 6 is a front, left-side and top perspective view thereof;

FIG. 7 is a front, right-side and top perspective view thereof;

FIG. 8 is a right side view thereof;

FIG. 9 is a left side view thereof; and,

FIG. 10 is a top view thereof.

The broken lines represent portions of the tool and form no part of the claimed design.
